UNITED STATES PATENT OFFICE.

HENRY E. OLSEN, OF CHICAGO, ILLINOIS, ASSIGNOR TO ACCOUNTING DEVICES COMPANY, OF CHICAGO, ILLINOIS, A CORPORATION OF ILLINOIS.

BINDER.

1,370,149.

Specification of Letters Patent.

Patented Mar. 1, 1921.

Application filed May 23, 1918. Serial No. 236,115.

To all whom it may concern:

Be it known that I, HENRY E. OLSEN, a citizen of the United States, residing at Chicago, in the county of Cook and State of Illinois, have invented a new and useful Improvement in Binders, of which the following is a specification.

This invention relates particularly to binders employing ball-lock devices for securing a clamping member to the posts.

The primary object of the invention is to provide an improved device for detachably locking the adjustable clamping member or clamping-members to the posts.

The invention, in its preferred embodiment, is illustrated in the accompanying drawings, in which—

Figure 1 is a broken plan view showing the upper side of a clamping-member which is attached to a cover-section and has the invention applied thereto; Fig. 2 is a broken plan view showing the underside of the clamping-member and cover-section; Fig. 3 is a plan view showing the lower clamping-member which carries the posts and is connected to the lower cover-section; Fig. 4 is an enlarged broken sectional view taken on the line 4 of Figs. 2 and 3 and Fig. 5 is an enlarged broken sectional view taken on the line 5—5 of Fig. 4.

Referring to the drawings, A represents a lower cover-section which has a clamping-member A¹ from which rise posts B; and C, an upper-cover section, with which is connected a clamping-member C¹ adjustably mounted on said posts.

The cover-sections A and C are preferably provided with hinge-eyes 10 which are connected by pins 11 to the hinge-eyes 12 on the edges of the clamping-members A¹ and C¹.

The lower clamping member A¹ may be of any suitable or approved construction. As shown in this instance, it comprises a sheet member 13 bent into hollow form and having the edges on its inner side separated to provide the longitudinal slot 14. Blocks 15 to which are connected the lower ends of the posts B are placed within the clamping-member A¹ and secured in position by rivets 16. In the end portions of the hollow member 13 are fitted the end-plugs 17 which are secured in place in any suitable manner, as by screws, or rivets, 18.

The upper clamping-member C¹ is made

hollow to contain the improved devices for releasably locking it to the posts B, and it preferably consists of a sheet-metal member 13¹ which is formed similarly to that of the lower clamping-member A¹ to provide the longitudinal slot 14¹ on its underside, and which has in its end portions the plugs 17¹ which may be similar to those on the clamping-member A¹ and which may be similarly secured in position by rivets 18¹.

The improved devices for releasably locking the clamping-member C¹ to the posts B are each constructed as follows:

A block 19 which is suitably positioned within the sheet metal member 13¹ is formed to provide a longitudinal slot 20, a vertical bore 21 for the post B which passes through the sheet-metal member 13¹, and an intersecting inclined or downwardly converging bore 22 in which is arranged the ball 23. A cam-lever 24 is disposed in the longitudinal slot 20 and is mounted on the transverse pivot 21¹. Through a longitudinal slot 25 which is provided in the depression 26 in the upper part of the sheet-metal member 13¹ extends a vertical stud 27 which is carried by the button 28 which latter is slidably movable on the clamping-member C¹. The stud 27 is adapted to contact with the cam surface 29 which is provided on the cam-lever 24, and the button 28 preferably is arranged in the depression 26 so that it is below or flush with the outermost surface of the clamping-member C¹. A small coil-spring 30 is confined in a bore 22^a in the block 19 and below the upper wall of the clamping-member, and serves normally to depress the end of the lever to throw the ball into frictional contact with the binding-post. The lever has a forked end engaging the ball, and is adapted to lift the ball against the force of the spring.

As will be seen in Figs. 4 and 5 of the drawings, the bore 22 converges downwardly and toward the post-bore 21, and said bore 22 intersects the bore 21 along one side so as to provide the tapered slot 31 through which the ball 23 will project slightly into the post-bore 21.

From the foregoing description, the construction, operation and advantages of the improved locking device will be readily apparent to those skilled in the art. It will be understood that when the upper clamping-member C¹ is fitted on the posts B and

is moved down on said posts to clamp the sheets, the balls 23 will not interfere with such action; but any upward pressure upon the upper clamping-member causes the balls 23 to bind between the posts B and the downwardly-converging walls of the bores 22. The springs 30 tend to force the balls 23 downwardly and into locking engagement with the posts B, this action occurring because the balls 23 are crowded between the posts B and the walls in the lower portion of the bores 22. The balls 23 can be released from the posts B by sliding the buttons 28 to cause the studs 27 to move in contact with the cam surfaces 29 so that the levers 24 are actuated to lift the balls 23 to the upper portions of the bores 22 where they are out of frictional engagement with the posts B.

20 It will be evident that the improved locking device is simple and effective, and that the clamping-member C¹ cannot be accidentally released from the posts B by pressure exerted axially of the studs 27.

25 The invention may be usefully employed in connection with binders for book-posting purposes of the character described, in the application of Arthur J. Lloyd, No. 236,836, filed May 24, 1918. In any case it is desirable to employ the sliding cams for actuating the ball-actuating levers, as thereby is obviated the danger of accidental release when the binder is thrown upon a table.

No unnecessary limitation should be understood from the foregoing detailed description which has been given for clearness of understanding only; but the appended claims should be construed as broadly as is permissible in view of the prior art.

40 What I regard as new and desire to secure by Letters Patent is—

1. A binder comprising a post, a clamping-member having a bore receiving said post, a supporting block secured in said clamping-member and provided with a post-bore and with an intersecting ball-bore, a ball in the ball-bore of said block, a cam-

lever pivotally mounted on said block and adapted to move said ball relatively to said post to effect release of the ball from the post, and a slideable member working in a slot in the outer longitudinal wall of said clamping-member and adapted to actuate said cam-lever.

2. A binder comprising a post, a clamping-member movably fitted on said post, a ball arranged in said clamping-member and adapted to frictionally engage said post, a lever provided with a cam surface and pivotally mounted in the clamping-member, said lever being adapted to move said ball relatively to said post, and a stud slidably mounted on said clamping-member and adapted to contact with said cam surface to actuate said lever.

3. A binder having a clamping-member fitted on a post, a ball arranged in said clamping-member and adapted to frictionally engage said post, a lever pivotally mounted in said clamping-member and engaging said ball, said lever being provided with a cam surface, a spring serving to press said lever in such direction as to force said ball into gripping engagement with said post, and a member slidably mounted in said clamping-member and adapted to contact with said cam surface to actuate said lever to move said ball out of engagement with said post.

4. In a binder, the combination of a clamping-member formed with a depression, a post passing through said clamping-member, a ball arranged in said clamping-member and adapted to frictionally engage said post, a lever provided with a cam surface, said lever pivotally mounted in said clamping-member and adapted to move said ball out of frictional engagement with said post, spring means tending to hold said ball in the gripping position, a slidably movable button arranged in said depression, and a stud on said button adapted to contact with said cam surface.

HENRY E. OLSEN.
